G. R. RICH

VALVE TAPPET AND LIKE ARTICLE

Filed June 8, 1925

Fig. 5.

Inventor:
George R. Rich,
by Charles Sherry
his attorney

UNITED STATES PATENT OFFICE.

GEORGE R. RICH, OF BATTLE CREEK, MICHIGAN.

VALVE TAPPET AND LIKE ARTICLE.

Application filed June 8, 1925. Serial No. 35,543.

To all whom it may concern:

Be it known that I, GEORGE R. RICH, a citizen of the United States, and a resident of Battle Creek, Calhoun County, and State 5 of Michigan, have invented certain new and useful Improvements in Valve Tappets and like Articles, of which the following is declared to be a full, clear, and exact description.

10 This invention relates to valve tappets and like articles of manufacture for use in internal combustion engines, and its principal object is to provide a two piece article having a disc like head and a hollow stem 15 united in a novel manner by a forging process. Another object is to provide a headed, hollow stem article, of which the stem may be formed of one forgeable metal and the head of the same at a different forgeable 20 metal. Among the advantages of a hollow stem or thin shell stem valve tappet are the lightness in weight, the saving of power and the economy in the use of gasoline or other explosive mixtures used in internal combustion 25 engines. Another object is to provide a more effective union between the head and hollow stem of valve tappets or other headed articles of manufacture, whereby the possibility of separation between the two under 30 hard usage, is entirely eliminated.

With these ends in view, this invention consists in a headed article of manufacture having a hollow stem, united therewith by a forging process in which the end of the 35 hollow stem is spread outward and laterally into the head portion during the forging process. It further consists in a headed article of manufacture having a hollow stem, the end portion of which is spread outward 40 and laterally into the head portion, during the forging process, and a part below the flared portion is forced inward into the interior of the hollow stem portion and into intimate contact with that side of the head 45 adjacent the stem. The invention further consists in the several novel features hereinafter fully set forth and claimed.

The invention is clearly illustrated in the drawings accompanying this invention, in 50 which:—

Fig. 1 is a side elevation of a valve tappet illustrating one embodiment of the present invention; Fig. 2 is a central longitudinal section therethrough; Fig. 3 is a side elevation of the two assembled pieces from which

the tappet is constructed; Fig. 4 is a cross section taken on the line 4—4 of Fig. 2; Fig. 5 is a central longitudinal section through fragments of forming dies, employed in the process of forming up the 60 tappet, the two pieces from which the tappet is formed, being also shown in central, longitudinal section; Fig. 6 is an end view of the piece, from which the head is formed, the view being taken in the direction indicated 65 by the arrow 6 in Fig. 3, and Fig. 7 is an end view of the piece from which the stem is formed, the view being taken in the direction indicated by the arrow 7 in Fig. 3.

Referring to said drawing, which illustrates one embodiment of the present invention applied to a valve tappet, the reference character 10 designates the head and 70 11 the stem of the tappet. The head may be of the usual disc like formation, composed 75 of any desirable forgeable metal suitable for withstanding the usual wear occasioned thereon by the cams of internal combustion engines, as is well understood. The stem is hollow and as a preference is formed from 80 a piece 11^a of metal rod bored lengthwise of itself from one end to leave a thin shell 12 (see Fig. 5) and a solid end 13. The metal of which the stem is composed may be the same kind or different from that 85 of which the head is formed. For instance, the head may be formed of alloys, containing tungsten, or chrome steel, chrome nickel steel, silicon iron and so forth. The stem may be formed of straight steel or 90 other suitable steels as is found most desirable.

In the finished article the solid end 13 is usually bored out and tapped as at 14 (see Fig. 2) for the usual adjustment stud (not 95 shown). The head and hollow stem are united in a novel manner by a forging process, and the method of constructing and uniting the parts will now be described.

Referring to Figs. 3, 5, 6 and 7 the head 100 of the tappet is formed from a cup like head piece 10^a of suitable dimensions to form the tappet head. Said head piece 10^a has an end wall 10^b and an annular side wall 10^c, the internal diameter of which is 105 made to receive the hollow stem piece 11^a.

In assembling the two pieces 10^a, 11^a and forming them up into a tappet, the head piece 10^a is slipped upon the stem piece 11^a and temporarily secured thereon by fric- 110

tion or otherwise. The assembled article is then placed in a furnace and heated to a forging temperature. It is then placed in a die A, which has an intaglio design or 5 countersink a, formed in its upper face, which corresponds to the side 15 and edge of the tappet head. The die is placed in the anvil of a suitable power hammer (not shown) and the hammer arm set in motion. 10 The arm carries a suitable heading die A¹ which strikes the parts of the article that protrude above the countersink a, in the die A, and drives them down upon the face of the countersink a, where the head piece 15 10^a, and end part 11^b of the hollow stem piece 11^a (Fig. 5) are spread outward and laterally into the shape illustrated in Fig. 2. The side wall 10^c of the head piece 10^a, or a considerable portion thereof, is forced upon 20 the face of the countersink, and the part 11^b of the stem piece, which is within the head piece, follows it and forms the thin widely flaring part 16 seen in Fig. 2. When the 25 illustrated shape of countersink a, is used, the lower edge 10^d of the head piece is forced into the side of the tappet as shown in Fig. 2. The outer portion of the top of the head piece 10^a is forced down upon the widely flaring part 16 of the stem 11, and 30 the unsupported middle part of the top is bulged inward toward the hollow of the stem as at 17. The part of the stem piece adjacent the lower edge of the head piece being unsupported, is forced inward into 35 the hollow of the stem piece, thereby forming an annular shoulder 18. The part of the tappet head 10 which protrudes beyond the stem piece, being supported by the die during the final hammering strokes, is com- 40 pacted, and those parts are effectively united against possible separation, because of the intimate contact formed between them. They are, to all intents and purposes, forged together into an integral piece and the un- 45 supported interior parts are forced into close and intimate contact. Because of the fact that the relatively thin, widely flaring part 16 of the stem, is embedded in the head portion, and presents relatively wide areas 50 of contact to the metal of the head, incipient fusion takes place during the forging opera- 55 tion and the head and stem are thereby effectively united to such an extent, that the usage to which they are subject in a motor, does not cause separation between them. Furthermore, the inwardly pressed annular part being in intimate contact with the ad- 60 jacent side of the head, it acts as a shoulder and takes up its portion of the shock, jar and pressure occasioned by the passage of the cam across the end face of the tappet. Furthermore, said shouldered part rein- 65 forces the stem at its place of connection with the head.

65 The advantages of a hollow stem valve

tappet are well known, lightness in weight, saving of power and increase in mileage are some of them. The principal objections to two piece valve tappets, in which the head portion is welded to the stem, is the danger of separation between the two pieces from ordinary use in a motor. Moreover, such tappets are comparatively costly to produce, and the difficulty of welding together metals of widely different fusing points is apparent. At best, only poor results are obtained. Valve tappets made in accordance with the present invention have overcome all of these obstacles and provide a highly efficient, durable and serviceable article. 70 75 80

More or less variation of the exact details of construction is possible without departing from the spirit of this invention; I desire, therefore, not to limit myself to the exact form of the construction shown and described, but intend, in the following claims, to point out all of the invention disclosed herein. 85

I claim as new, and desire to secure by Letters Patent:

1. As a new article of manufacture, a forged, headed stem, composed of two pieces of forgeable metal, and comprising a disc like head portion and a stem portion, irre- 95 movably secured thereto, one end of the stem portion being concave and having a widely flaring laterally extending end part em- bedded in that part of the metal of the head which projects beyond the sides of the stem, the metal of the head portion being thick- 100 ened at its middle part and entering the concave space in the flaring end part of the stem, and both faces of said flaring end part being held in intimate contact with and by the contiguous metal of the head portion, located on opposite sides of said flaring end part of the stem. 105

2. As a new article of manufacture, a forged valve tappet, composed of two pieces of forgeable metal, and comprising a disc like head portion and a hollow stem portion, irre- 110 movably secured thereto, the hollow stem portion having a widely flaring, laterally extending end part embedded in that part of the metal of the head which projects be- 115 yond the stem and the metal of the head portion being thickened at its middle part and entering the space contained in the flaring end part of the hollow stem and both faces of said flaring end part being in, 120 intimate contact with the contiguous metal of the head portion located on opposite sides of said flaring end part of the stem.

3. A two piece valve tappet, composed of forgeable metals and comprising a forged together disc like tappet head portion and a hollow tappet stem portion, the hollow tappet stem portion having a thin, widely flaring end part embedded in that part of the disc like head portion which pro- 125 130

trudes beyond the side of the stem portion, and an inwardly projecting annular shoulder in intimate contact with the side of the head adjacent the stem portion.

5. 4. A two piece valve tappet, composed of forgeable metals and comprising a forged together disc like tappet head portion and a hollow tappet stem portion, the head portion having a middle portion bulging toward

the stem portion, and the hollow tappet stem 10 portion having a thin, widely flaring end part embedded in that part of the disc like head portion which protrudes beyond the side of the stem portion, and an inwardly projecting annular shoulder in intimate contact with the bulged side of the head adjacent the stem portion. 15

GEORGE R. RICH.
